G. E. LLEWELLYN

COLLAPSIBLE BOTTLE HOLDER

Filed Feb. 10, 1922

Minnow:
R. E. Leiber

UNITED STATES PATENT OFFICE.

GEORGE E. LLEWELLYN, OF EAU CLAIRE, WISCONSIN, ASSIGNOR, BY MESNE ASSIGNMENTS, TO SANITARY NOVELTIES COMPANY, A CORPORATION.

COLLAPSIBLE BOTTLE HOLDER.

Application filed February 10, 1922. Serial No. 535,565.

To all whom it may concern:

Be it known that I, GEORGE E. LLEWELLYN, a citizen of the United States, and resident of Eau Claire, in the county of Eau Claire 5 and State of Wisconsin, have invented certain new and useful Improvements in Collapsible Bottle Holders; and I do hereby declare that the following is a full, clear, and exact description thereof.

10 The invention relates to devices for supporting milk bottles. It comprises a back plate, a shelf and means for supporting the shelf in a horizontal position, but permitting its collapse to a flat position.

15 The primary object of the invention is general convenience. When each family living in large apartment buildings has a container, the milkman is aided in such a manner as to know at a glance where to deliver the milk. Thus the customer is assured of reliable service.

20 The annoyance caused by animals is overcome as the container is fastened to a wall out of reach. Children also are prevented 25 from tampering with the bottle, thus eliminating danger to the children, as well as possibility of breakage of the bottle.

25 An important object is cheapness of manufacture, the device being made entirely of sheet metal and wire worked in a convenient manner.

30 An additional object is the provision of a structure which is collapsible so as to take up a minimum quantity of space, being perfectly flat, and yet which is capable of being readily expanded to its normal useful position, and secured suitably to a wall.

35 A feature is the provision of a simple and effective lock, whereby the shelf is maintained horizontal, danger of collapse being eliminated.

40 With the above and other objects in view which will appear as the description proceeds, my invention resides in the novel construction, combination and arrangement of parts substantially as hereinafter described and more particularly defined by the appended claims, it being understood that such changes in the precise embodiment of the 45 herein disclosed invention may be made as come within the scope of the claim.

50 In the accompanying drawing, I have

illustrated one complete example of the physical embodiment of the present invention constructed according to the best mode 55 I have so far devised for the practical application of the principles thereof, and in which—

Figure 1 is a front elevation of the device with the shelf in elevated position. 60

Figure 2 is a cross section thereof on the line 2—2 of Figure 1, and

Figure 3 is a view of the device in collapsed position.

Back plate 10 is provided with apertures 65 11 and a slot 12, by means of which a tongue 13 is formed for the reception of tickets, orders and the like. The U supports 14 are made rigid with the back plate 10, and straps 15 are secured to the bottom of back plate 70 10, one end of each strap being in front, and the other in the rear, rivets 16 making the ends rigid with back plate 10. The middle portion 17 of straps 15 is outwardly directed 75 and a piece of wire 17' extending rectangularly is rotatably positioned therein. Shelf 18 has its edges on all sides bent about wire 17', the shelf being cut away at the corners.

A substantially U shaped wire 20 is secured at its ends by eyes 19 to wire 17', shelf 80 18 being cut away suitably for the reception of eyes 19 and straps 16. U shaped wire 20 has three loops 22—22—22 therein, to which the eyes 23—23—23 of rods 24—24—24 are secured, these rods having angularly directed 85 arms 25—25—25 adapted to extend thru U supports 14. The rods are secured together by spacer 21. It will be noted that the rigidity of arms 25—25—25 is such as to support shelf 18 in horizontal position. Thus 90 a convenient raising means is provided readily placed in operative position.

When it is desired to collapse shelf 18, rods 24—24—24 are moved upwardly and arms 25—25—25 are disengaged from U supports 14, so that the entire device may be collapsed, shelf 18 pivoting on wire 17, as does also wire 20. 95

I claim:

The combination of a back plate, a pair 100 of straps secured at the bottom edge thereof, the middle of said straps being outwardly directed, a wire extending in a substantial rectangle, rotatably secured in said straps,

a shelf having its ends formed into eyes secured to said first wire, said second mentioned wire having three loops formed therein, three rods each having an end formed into an eye pivoting on one of said loops, the other ends of said rods being extended at an angle to said rods, and eyes on said

back plates for receiving said ends and locking said shelf in raised position.

In testimony that I claim the foregoing I 10 have hereunto set my hand at Eau Claire, in the county of Eau Claire and State of Wisconsin.

GEORGE E. LLEWELLYN.
